(57) **CLAIM**

The ornamental design for a hose sleeve, as shown and described.

DESCRIPTION

FIG. 1 is a top perspective view of a first embodiment of a hose sleeve showing the new design;

FIG. 2 is a bottom perspective view of the embodiment of FIG. 1;

FIG. 3 is a left elevation view of the embodiment of FIG. 1; FIG. 4 is a right elevation view of the embodiment of FIG. 1;

FIG. 5 is a top plan view of the embodiment of FIG. 1;

FIG. 6 is a bottom plan view of the embodiment of FIG. 1;

FIG. 7 is a front elevation view of the embodiment of FIG. 1;

FIG. 8 is a rear elevation view of the embodiment of FIG. 1;

FIG. 9 is a top perspective view of a second embodiment of the hose sleeve showing the new design;

FIG. 10 is a bottom perspective view of the embodiment of FIG. 9;

FIG. 11 is a left elevation view of the embodiment of FIG. 9;

FIG. 12 is a right elevation view of the embodiment of FIG. 9;

FIG. 13 is a top plan view of the embodiment of FIG. 9;

FIG. 14 is a bottom plan view of the embodiment of FIG. 9;

FIG. 15 is a front elevation view of the embodiment of FIG. 9; and,

FIG. 16 is a rear elevation view of the embodiment of FIG. 9.

The stipple shading and the curved shading along the end of the ties illustrate a contrast in appearance.

The broken lines shown in the figures are for the purpose of illustrating portions of the hose sleeve and form no part of the claimed design.
